Primary Examiner — Jeffrey D Asch*Assistant Examiner* — Caitlin A Laverty(74) *Attorney, Agent, or Firm* — Fish & Richardson P.C.(57) **CLAIM**

The ornamental design for a holster for retractable device, as shown and described.

DESCRIPTION

FIG. 1 is a top perspective view of the holster for retractable device.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines illustrate environmental features that form no part of the claimed design.
